Specification of Letters Patent. Patented Dec. 12, 1916.

Application filed March 23, 1914. Serial No. 826,471.

To all whom it may concern:

Be it known that I, HERBERT R. GOODFELLOW, a subject of the King of England, residing at Chicago, in the county of Cook and State of Illinois, have invented certain new and useful Improvements in Slicing-Machines, of which the following is a specification.

This invention relates in general to slicing machines, but more particularly to the mechanism for holding and for feeding or advancing the article to be sliced.

Heretofore in machines of this character, the article is advanced to the cutter, through the medium of what is called the feeding table and to which table the article is secured or clamped by a clamping bar, that is adjustably supported by means of two uprights connected with the table. The article is positioned on the table so that a portion thereof will project in advance of the clamping bar and beyond the supporting table; and after the clamping bar is adjusted to secure the article, the table is advanced with respect to the carriage, during the operation of the machine, to intermittently advance the article to the cutter. After the article has been cut until the clamping bar assumes a position in close proximity to the cutting blade, the machine is stopped, the table retracted and the clamping bar adjusted to release the article, to permit the latter to be again adjusted with respect to the table, and then clamped by the clamping bar, to again leave a portion of the article projecting in advance of the clamping bar. This operation is repeated as often as necessary, or until the article has been cut up, or the desired quantity cut therefrom. This constant clamping and unclamping of the article and the adjustment of the article, not only necessitates considerable time, but the pressure of the clamping bar upon the article, not only mars or bruises the article, but tends to crush or break the same, under the pressure. To overcome these objections and difficulties, and to provide an improved machine of this character having means whereby the article, after being once placed in position, may be continuously fed to the cutter until the entire article has been cut or the desired quantity cut therefrom, without shifting or re-adjusting the article with respect to the

feeding mechanism, is one of the objects of the present invention.

A further object is to provide an improved machine of this character having means whereby the article may be sufficiently and properly held to be cut, and the usual clamping bar may be dispensed with.

A further object is to provide an improved machine of this character having means for continuously feeding and holding the article without shifting or changing the position of the article with respect to the feeding mechanism, until the desired amount has been cut, and which holding mechanism will automatically compensate the varying sizes and irregularities of the different portions of the article.

To the attainment of these ends, and the accomplishment of other new and useful objects as will appear, the invention consists in the features of novelty, in substantially the construction, combination and arrangement of the several parts hereinafter more fully described and claimed and shown in the accompanying drawings illustrating the invention and in which—

Figure 1 is a front elevation of a slicing machine having an attachment applied thereto constructed in accordance with the principles of this invention. Fig. 2 is a top plan view of the parts shown in Fig. 1. Fig. 3 is a detail sectional view taken on line 3—3, Fig. 2. Fig. 4 is a detail sectional view taken on line 4—4, Fig. 8. Fig. 5 is a detail sectional view taken on line 5—5, Fig. 3. Fig. 6 is a detail view in elevation taken on line 6—6, Fig. 3. Fig. 7 is a detail view taken on line 7—7; Fig. 3. Fig. 8 is a view similar to Fig. 5 with parts in elevation and parts omitted. Fig. 9 is an enlarged top plan view of a portion of the machine and of the article holding and clamping means partly in elevation, partly in section and with parts broken away. Fig. 10 is an enlarged detail view partly in elevation and partly in vertical section of a modified form of clamping and holding means.

Referring more particularly to the drawings and in the present form of the invention, the numeral 10 designates generally a supporting structure, 11 designates a rotary cutter which is operated from the fly

wheel 12. Mounted to reciprocate upon tracks or guides 13, 14 supported by the base of the machine is a carriage 15, which receives its motion from a crank 16 connected with a shaft 17, driven from the main driving shaft of the machine, and through the medium of a link 18 which is pivotally connected as at 19 with the shaft and as at 20 with the carriage 15, so that when the fly wheel 12 is rotated, motion will not only be imparted to the cutter, but the carriage 15 will be reciprocated on the guides 13, 14. All of these parts may be of the ordinary construction and are well known in this art.

Carried by the carriage, and preferably arranged centrally thereof, so as to extend longitudinally of the carriage, and journaled in suitable bearings is a feed screw 21, which is preferably arranged below the carriage and in alignment with a slot 22 which extends through the carriage and also longitudinally thereof. This screw 21 is adapted to be intermittently rotated when the carriage is reciprocated, and for that purpose there may be provided an arm 23, which is loosely journaled by one extremity, preferably upon a projecting extremity of the screw 21. The arm 23 is provided with a portion 24, that carries a pawl 25, the latter being pivoted to the portion 24 so as to coöperate with a ratchet wheel 26 that is secured to the screw 21, and an elastic member 27 may be provided which tends normally to hold the pawl 25 in engagement with the ratchet wheel 26. Arranged within the path of movement of the arm 23 by the reciprocation of the carriage 15, is an adjustable abutment 28, and an anti-friction roller 29 may be provided on the arm 23 to engage the abutment. It will thus be seen that when the carriage is reciprocated and moved in one direction, the anti-friction roller 29 will engage the abutment 28 and will rock the arm, this in turn will rock the portion 24 of the arm to move the pawl 25 to rotate the ratchet element 26 and also the feed screw 21. An elastic member 30 may be provided which tends to turn the arm 23 when the carriage moves in a direction to move the arm away from the abutment 28. Obviously the extent of rotation of the screw 21 will be controlled by the extent of movement of the arm 23, and the extent of movement of the latter will be controlled by the position of the abutment 28.

Mounted to slide upon the carriage 15 is an element 31 which is provided with an upright portion 32, the element standing astride of the slot 22 on the table 15. Depending from the element 31 is a projection 33, here shown as comprising spaced portions which enter the slot 22 and have laterally projecting portions 34 which extend under the carriage top. In order to permit this

element 31 to be removed when desired, the carriage top may be provided with a removable section 35, which extends along a portion of one of the walls of the slot 22 and this section 35 may be removably held in position by means of fastening devices 36, so that when it is desired to remove the element 31, all that is necessary is to remove the fastening devices 36 and lift out the section 35, after which the portions 33 on the element 31 can be removed from the slot. Obviously any other suitable means may be provided for removably securing the element 31 to the carriage.

Arranged upon the upright portion 32 of the element 31 are a plurality of articles engaging prongs 37, here shown in the form of spirals, which are rotatably supported by the portion 32 to project beyond the face thereof, and connected with each of these screws 37 is a gear wheel 38, and these gear wheels are intermeshed so that when one of the gears is rotated by means of a handle 39 connected therewith, all of the other gears will be rotated and consequently the corresponding screws 37. With this construction it will be manifest that when it is desired to connect an article with this feeding element 31, all that is necessary is to hold the end of the article against the screws, and then rotate the handle 39, which will cause the screws 37 to enter the article and thereby secure it to the element. The article is fed by advancing this element 31 by the rotation of the screw 21, and in order to accomplish this there is provided what is commonly known in this art as a half nut 40 that is connected with a stem 41. The nut 40 projects through the opening 22 to engage the screw 21, and the stem 41 projects through the element 31 and also through a tubular casing 42 and to the extremity of the stem is pivoted a cam device 43 which coöperates with the closed end 44 of the housing 42 to raise and lower the half nut with respect to the screw 21. An elastic member 45 in the form of a coil spring is provided which surrounds the stem 41 within the housing 42 and tends normally to move the half nut 40 into engagement with the screw. Thus it will be manifest that when the half nut is in engagement with the screw, and the latter rotated, the article will be fed forwardly to the cutter 11, and when the cam device 43 is shifted to raise the half nut 40 out of engagement with the screw, the element 31 and the article, if the latter is attached thereto, may be readily moved up on the carriage independently of the screw.

If desired a crank 46 may be connected with the screw 21 for rotating the same. The article holding or clamping means for maintaining the article in position and for holding it securely while being cut by the

cutter and during the reciprocation of the carriage, embodies spaced uprights 47, 48, which are arranged adjacent the front of the carriage 15, and in close proximity to the cutter 11. These uprights are adapted to be moved toward and away from each other and the article to be cut is fed between the uprights, the upright 48 engaging one side of the article, while a clamping element 47^a, 5 carried by the other upright 47 engages the other side of the article and coöperates with the upright 48 to clamp the article, thereby obviating the necessity of the ordinary and well known clamping bar. These uprights 10 47, 48 are preferably supported by means of a bar or guide 49, arranged adjacent the front of the carriage and the uprights are provided respectively with body portions 50, 51, that move beneath the top of the carriage 15 and through which body portions the support 49 loosely passes. These bodies 20 50, 51 are preferably of some length to prevent the uprights from rocking, and the uprights pass through slots 52, 53 provided for that purpose, adjacent the front of the carriage. The support 49 is preferably angular in cross section and the apertures through the bodies 50, 51 through which the support passes, are of the same configuration. 25 The uprights are adapted to be moved toward and away from each other to move the clamping elements into and out of clamping relation, and in order to obtain this movement, the uprights have respectively connected thereto arms 54, 55 by 30 means of pin and slot connections 56, 57 and the arms are respectively supported by means of pivots 58, 59, stop devices 60, 61 being provided and against which the arms 35 40, abut, to limit the movement of the clamping elements toward each other. Obviously the slots 56, 57 may be formed in separate plates which may be secured respectively to the bodies of the uprights.

45 An elastic member 62 is connected by one extremity to the arm 54 and is anchored by the other extremity to a fixed support, and a similar elastic member 63 is anchored by one extremity to the arm 55 and by the other 50 extremity to a fixed support. These elastic members 62, 63 tend normally to move the arms 54, 55, and consequently the uprights 47, 48 in a direction toward each other to clamp the article. In order to separate the 55 clamping elements 47^a and 48, to permit the article to be positioned therebetween, there is provided a lever 64 which is pivotally supported as at 65 intermediate its ends and projects beyond the side of the carriage 15, 60 terminating in an upright portion 66 by means of which the lever 64 may be moved about its pivot.

Pivots connected with the arm 54 is a link 67 having a slot 68 and a similar link 69 is pivotally connected to the arm 55 and

is provided with a slot 70. These slots 70 are adapted to receive a pin 71 which is connected with the lever 64 and which pin travels in the slots when the lever is moved. To swing the arms 54, 55 about their pivots 70 in a direction to separate the uprights 47, 48, and against the stress of the elastic members 62, 63, the lever 64 is moved about its pivot 65 so that the pin 71 will be moved in a direction toward the uprights. This 75 will cause the pin 71 to engage the ends of the slots 68, 70 and will through the medium of the links 67, 69 rock the arms 54, 55 about the pivots 58, 59 and the uprights will be maintained separated as long as the lever 80 is held in that position. When the article is positioned between the clamping elements 47^a and 48, the lever 64 may be released, at which time the stress of the elastic members 62, 63 will move the arms 54, 55 in directions to draw the clamping elements toward each other and against the sides of the article. A stop 72 may be provided for limiting the movement of the lever 64 under the stress of the elastic members 62, 63. 90

In order to maintain the arms 54, 55 separated, and lock the lever 64 in its adjusted position, a spring catch 73 may be provided having a cam portion 74 adapted to coöperate with the stop 75. 95

It will thus be manifest that when the article is secured to the element 31, and the latter is adjusted so that the article will project between the clamping elements 47^a and 48, the elastic members 62, 63 will cause 100 the uprights to clamp the sides of the article. When in this position the article is ready to be sliced. When the machine is set into motion, the carriage 15 will be reciprocated in the ordinary manner and the 105 article will be intermittently advanced to the cutter through the medium of the feed screw 21 and the arm 23 and abutment 28. In order to hold the article against lateral displacement by the engagement 110 therewith of the cutter, it is necessary to provide some abutment against this movement, and therefore there is provided an automatic locking device for locking the clamping element 47^a against retrograde 115 movement. This locking device may be of any suitable construction, but a simple and efficient lock comprises an element 76, (see particularly Fig. 10), which is provided with an opening 77 through which the bar 120 or support 49 passes. This element 76 is pivotally connected as at 78 with the body 50 of the upright 47 and an elastic member 79 is provided between the body and the element which tends normally to separate 125 the two. The element 76 is preferably arranged on one end of the body and between the pin 56 of the arm 54 and the adjacent end of the body. This element 76 is so arranged that it will permit the upright 47 130

and the clamping element 47^a to move freely toward the clamping element 48 under the stress of the elastic member 63 but will lock the clamping element 47^a and its supporting upright against retrograde movement. Thus it will be manifest that when the article is passed between the clamping elements, and the carriage is advanced so that the cutter engages the article, there will be 10 a tendency of the cutter to shift the article laterally on the table, but this shifting movement will be overcome or restricted by the clamping element 47^a, because any tendency to move this element away from the clamping element 48 will cause the element 76 to lock the clamping element 47^a against retrograde movement.

When it is desired to separate the clamping elements so as to permit another article 20 to be positioned therebetween, this is accomplished by swinging the lever 64 which will rock the arms 54, 55 in the manner already described and during this rocking movement the pin and slot connection 56, 57 between the arm 54, and the upright 47, carrying the clamping element 47^a, will permit the pin 56 to move in the slot 57 sufficiently to shift the element 76 with respect to the body portion of the upright, into such position 30 that the opening 77 in the element 76 will be positioned in alignment with the opening in the body 50, which will allow the upright 47 to move freely in either direction with respect to the bar or support 49.

35 Obviously a locking element 80 similar to the locking element 76 may be provided for the clamping element 48, and if desired a roller 81^a may be provided on the element 48 to reduce the friction of the element on 40 the side of the article.

As the article is fed between the clamping elements, the elastic members 62, 63 tend normally to hold the element against the side of the article, and it will therefore be 45 seen that the elastic members and clamping elements will compensate the varying sizes or irregularities of the article, inasmuch as the elastic members will cause the clamping elements to follow the shape or 50 the size of the article. Furthermore, the clamping elements are adapted for independent movements toward and away from the respective sides of the article.

The clamping element 47^a is preferably 55 of a substantially L shape formation, and is pivoted intermediate its ends as at 81 to a collar 82 which is adjustably mounted on the upright 47, and a spring 83 is provided for holding the clamping element in the 60 position shown in Figs. 1 and 10 when not in use. This positions the clamping element to receive the side of the article and to coöperate with the element 48 to clamp the article.

65 The collar which supports the element 47^a

is adjustably held on the upright by means of a fastening device 85. The upright is preferably angular in cross section to maintain the clamping element 47^a in proper position.

70 While the preferred form of the invention has been herein shown and described, it is to be understood that many changes may be made in the details of construction and in the combination and arrangement of the several parts, without departing from the 75 spirit of this invention.

What is claimed as new is:—

1. In a slicing machine, a relatively movable article support and cutter, coöperating article side clamping elements, means controlling the clamping action of said elements, the said means yieldable to the movement of the article with respect to the clamping elements, said cutter during the cutting operation tending to force the article against one of the said clamping elements, means operating to automatically lock that one of the clamping elements against retrograde movement under such action of the cutter, and means for releasing the said locking means. 80

2. In a slicing machine, an article support embodying coöperating article side clamping elements, and means operating to move the elements in clamping direction one with respect to the other, the said means yieldable to the movement of the article with respect to the elements, one of the elements being mounted for adjustment in an upright plane toward and away from the support. 95

3. A device of the character described embodying coöperating clamping elements, means tending normally to render the elements active, said elements yieldable against the stress of the said means to permit the article to be fed with respect to the elements, mechanism automatically rendered active under the stress of the article for locking one of the elements against retrograde movement and means for rendering the last said mechanism inactive, the last said means also operating to separate the said elements and maintain them separated. 105

4. An article holder for slicing machines embodying an article support, coöperating clamping elements projecting above the support to clamp the sides of the article, means tending normally to move the elements in a clamping direction with respect to each other, and means individual to the elements and operating automatically to lock them against retrograde movement. 120

5. An article holder for slicing machines 125 embodying an article support, opposed laterally movable article side clamps projecting above the support, means tending normally to impart a clamping action to the clamps, and means operating under the 130

- stress of the article upon one of the clamps to lock the latter against unclamping movement.
6. An article holder for slicing machines embodying an article support, opposed article side clamps, means tending normally to move the clamps into engagement with the article, means operating automatically to hold one of the clamps against retrograde movement to form a cutting abutment for the article, and means for feeding the article between the clamps and while the clamps are in engagement with the article.
7. A device of the character described, embodying a support, opposed laterally movable article side clamps, means for moving and holding the clamps in engagement with the sides of the article, and means for locking one of the clamps against movement away from the article but permitting free movement of the clamp in a direction toward the article.
8. A device of the character described, embodying a support, opposed laterally movable article side clamps, means for moving and holding the clamps in engagement with the sides of the article, means for locking one of the clamps against movement away from the article, and means for unlocking the clamp, the last said means embodying mechanism for moving both of the clamps away from each other.
9. A device of the character described, embodying a support, opposed laterally movable article side clamps, means for moving and holding the clamps in engagement with the sides of the article, said means causing the clamps to automatically follow the contour of the article, and means for locking one of the clamps against movement away from the article but permitting free movement of the clamp in a direction toward the article.
10. A device of the character described, embodying a support, opposed laterally movable article side clamps, means for moving and holding the clamps in engagement with the sides of the article, said means causing the clamps to automatically follow the contour of the article, means rendered active by the stress of the article against one of the clamps for locking the latter against movement away from the article, and mechanism for releasing the clamps and for shifting the clamps against the stress of the first recited means.
11. A device of the character described, embodying a support, opposed laterally movable article side clamps, and means operating to yieldingly hold the clamps against the article, one of the clamps embodying an article engaging element mounted for pivotal movement in directions toward and away from the support.
12. A device of the character described, embodying a support, opposed laterally movable article side clamps, and means operating to yieldingly hold the clamps against the article, one of the clamps embodying an adjustable supported and pivotally mounted element, the element formed and positioned to engage the side of the article to be.
13. A device of the character described, embodying a support, opposed laterally movable article side clamps, means operating to yieldingly hold the clamps against the article, one of the clamps embodying an article engaging element mounted for pivotal movements in directions toward and away from the support, and means for feeding the article between the clamps.
14. A device of the character described, embodying a support, opposed laterally movable article side clamps, means operating to yieldingly hold the clamps against the article, one of the clamps embodying an article engaging element mounted for pivotal movements in directions toward and away from the support, and means for feeding the article between the clamps and while the clamps remain active.
15. A device of the character described, embodying a support, opposed laterally movable article side clamps, and means operating to yieldingly hold the clamps against the article, one of the clamps embodying a pivotally supported and vertically adjustable article adjusting element.
16. A device of the character described, embodying a support, opposed laterally movable article side clamps, and means operating to yieldingly hold the clamps against the article, one of the clamps embodying a support, an article engaging element mounted thereon for movement about a substantially horizontal pivot, and means tending to move the element about its pivot in a direction to engage the side of the article.
17. A device of the character described, embodying a support, opposed laterally movable article side clamps, and means operating to yieldingly hold the clamps against the article, one of the clamps embodying an element having spaced portions to receive the side of the article and mounted for pivotal movement in directions toward and away from the support.
18. A device of the character described, embodying a support, opposed laterally movable article side clamps, and means operating to yieldingly hold the clamps against the article, one of the clamps embodying an adjustably supported and pivotally mounted element, the element formed and positioned to engage the side of the article to be.

rocked about its pivot and into clamping position by the article.

19. A device of the character described, embodying coöperating article holding elements, means for feeding the article with respect to the said elements, means operating to move the elements in clamping direction with respect to each other, the said elements being adapted for movement toward and away from the article independently with respect to each other, and means operating to lock one of the elements against movement in a direction away from the other but permitting free movement of the element in a clamping direction.

15. 20. A device of the character described, embodying coöperating article holding elements, means for feeding the article with respect to the said elements, means operat-

ing to move the elements in clamping direction with respect to each other, the said elements being adapted for movement toward and away from the article independently with respect to each other, means operating to lock one of the elements against movement in a direction away from the other but permitting free movement of the element in a clamping direction, and means for releasing the last recited means.

In testimony whereof I have signed my name to this specification, in the presence of two subscribing witnesses, on this 12th day of March A. D. 1914.

HERBERT R. GOODFELLOW.
